UNITED STATES PATENT OFFICE.

JULIUS WYSS, OF WATERTOWN, MASSACHUSETTS, ASSIGNOR TO NEW ENGLAND SPUN SILK CORPORATION, OF NEW YORK, N. Y., A CORPORATION OF MASSACHUSETTS.

STOP MOTION FOR YARN-TWISTING MACHINES.

Application filed April 29, 1927. Serial No. 187,453.

This invention relates to improvements in yarn twisting machinery, and has particular reference to a stop motion device therefor.

An object of the invention is to provide 5 an improved stop motion device of simple and practical construction which will reduce to a minimum the waste involved when yarns become broken and will effectively operate to prevent what are known in the art as "double 10 ends", these occurring when yarns being twisted become broken and tangle with the twisted yarns which are being wound upon next adjacent bobbins.

Another object is to so construct the yarn 15 gripping means of the stop motion device that when said means is engaged with the yarns, following a break therein, it will cause the severance of the yarns at a point between the feeding spools and delivery 20 rolls to permit clearing of the detached ends by the action of said rolls and will, at the same time, hold the extremities of the yarns in such manner that when the operator removes the same from said means, preparatory 25 to again feeding the yarns between the delivery rolls, said extremities will readily become detached from the gripping means without leaving fine short strands of the material therein.

30 The above and other objects will appear more clearly from the following detail description, when taken in connection with the accompanying drawings, which illustrate a preferred embodiment of the inventive idea.

35 In the drawings—

Figure 1 is a fragmentary transverse sectional view taken through a yarn twisting machine and showing one of the improved stop motion devices applied thereto;

40 Figure 2 is a fragmentary top plan view of the machine, illustrating two of the stop motion devices each associated with one of the yarn delivery mechanisms of the machine;

45 Figure 3 is an end elevation of the improved stop motion device;

Figure 4 is a fragmentary plan view thereof;

50 Figure 5 is a section on the line 5—5 of Figure 3, showing the gripping means in operative position;

55 Figure 6 is a view similar to Figure 5, showing the gripping means of the stop motion device in its inoperative position, this position being taken only when extremities

of the yarns are being detached therefrom, following a break in the yarns between the delivery rolls and the spindle upon which the twisted yarns are being wound; and

Figure 7 is an elevational view of the end 60 of the stop motion device opposite that shown in Figure 3.

The twisting machine partially illustrated in the accompanying drawings is of a well known construction wherein the frame there- 65 of, generally indicated by the numeral 10 is of considerable length so as to provide for the simultaneous operation of a battery of spindles 11 supported and driven in the customary manner to wind the yarns there- 70 on and effect the twisting thereof between the spindles and the delivery rolls. In twisting frames of the usual construction there are provided one or two lower delivery rolls 12 which extend the entire length of 75 the machine and are therefore common to all of the spindles. Supported above and in engagement with the delivery roll or rolls 12 are a plurality of top rolls 13 each indi- 80 vidual to one spindle and with each of which there is associated one of the stop motion devices comprising the essential features of the present invention. At the rear of the frame 10 there is provided an upright 14 upon which are mounted a plurality of yarn 85 carrying spools or rolls 15 only one of which is shown in the present illustration. Assuming, for purposes of the present description, that a thread is to be made up and wound upon the bobbin 11 by twisting two lengths 90 of yarn, these lengths are fed from the spools 15 in parallel or untwisted relation and extended around a guide rod 16 ar- 95 ranged lengthwise of the machine. The yarns then are passed to and between the de- 100 livery rolls 12 and 13 which are operated in the usual manner to draw the yarns from the spools. From the rolls the yarns are wound upon the spindle 11 and the twisting action applied to the yarns takes place between said 105 rolls and the spindle. It is between these points that the yarns break and, due to the whirling action imparted to the yarns during the twisting operation, the broken ends will very often become tangled with the 110 yarns being wound upon next adjacent spindles on opposite sides of the spindle 11 causing what is known as "double ends". It is for the purpose of preventing these double ends that the stop motion devices are pro-

vided and each of these devices operate, upon the breaking of the yarns with which it is associated, to stop the further feeding of the yarns to the delivery rolls, the operation of 5 which continue after the break.

One of the stop motion devices and its operation will now be described in detail. A bearing block 17 is secured to a suitable part of the framework of the machine above 10 the delivery rolls 12, such as the support 18 for the top roll 13. An arm 19 is pivotally mounted, intermediate its ends, in the block 17 for rocking movement therein with one end of the arm disposed upon the inlet side 15 of the delivery rolls and its opposite end disposed upon the outlet side thereof, the downward movement of the first named end being limited by contact with the inclined edge 20 of said block, as illustrated in 20 dotted lines in Figure 1. The second named end of the arm 19 is provided with a depending offset extension 21 which terminates at its free extremity in a laterally projecting hook 22 through which pass the yarns 25 to be twisted. The tension applied to the yarns as they are being drawn on to the spindle 11 and the consequent downward pull upon the outer end of the arm 19 is sufficient to maintain said arm in its normally inoperative position shown in full 30 lines in Figure 1. However, should the yarns become broken between the hook 22 and the spindle 11, this tension is relieved and the arm 19, being slightly heavier on 35 the opposite side of its pivot from the hook 22, will immediately rock about said pivot to the dotted line position with the result that the yarns which normally pass freely beneath the gripping means of the device, 40 as shown in Figure 3, will be engaged by said means to cause a severance of the yarns at this point. This severing action is due to the continued pull exerted by the delivery rolls upon those portions of the yarns which 45 are at the time of the break passing between said rolls. Said portions, which will always be of comparatively short length thus reducing the waste to a minimum, will be drawn between the rolls and be either 50 wound upon the roll 13 or thrown off the rolls by the rapid rotation thereof.

The gripping means at the inner end of the arm 19 comprises a stationary plate 23 extending laterally from the arm and adjustably secured lengthwise thereof by means of a small bolt 24 extending through a slot 25 in said arm. The plate 23 and the remainder of the parts associated therewith are disposed diagonally relative to the arm 55 19 and at such an inclination that the gripping means will at all times be inclined upwardly and forwardly toward the front of the machine for a purpose which will presently appear. The upper edge of the plate 23 is provided with a boss 26 having a

transverse opening therethrough for receiving one end of an angular rod 27 adjustably secured in said boss by means of a screw 28. The opposite end of the rod 27 is utilized as a pivot for a movable gripping plate 29 which cooperates with the plate 23 to grip the yarns therebetween when the arm 19 is in its operated position. The plate 23 is provided with a beveled gripping surface 30 which is adapted to be engaged by the gripping edge or surface 31 of the plate 29, as shown in Figure 5, when the latter plate is in its normal position. This normal position of the plate 29 is assumed at all times except when the extremities of the yarns held between said plates are being withdrawn therefrom following the severance of the yarns at the point of engagement of the gripping means therewith and this normal engagement of the surfaces 30 80 and 31 is due to the inclination of the plates with respect to the arm 19. Thus when the inner end of the arm 19 falls, by reason of a break in the yarns, the gripping means comprising the plates 23 and 29 have their 85 gripping surfaces in contacting relation and will consequently engage the yarns as the latter pass into the re-entrant slot 32 formed between said plates by curving the lower edges thereof. As the yarns 90 come into contact with the surfaces 30 and 31 the continued pull upon the portions of the yarns between the gripping means and delivery rolls will cause said 95 yarns to be severed at the point of engagement of the gripping surfaces therewith with the result that no more of the yarns, with the exception of said portions, will be fed between the delivery rolls. The extremities of the yarns extending from the 100 spools 15 will now be held between the gripping surfaces and an operator upon observing a break will then detach said extremities from the gripping means preparatory to again feeding the yarns between the delivery rolls and to the spindle. In withdrawing the extremities of the yarns from the gripping device, it is highly desirable that no short strands thereof be left between the gripping surfaces and it is mainly for 105 this purpose that the plate 29 is pivotally mounted so that when a rearward pull is exerted upon the yarns said plate 29 will swing rearwardly about its pivot and thus disengage the surface or edge thereof from the beveled surface 30 of the plate 23, the rearward movement of said plate 29 being limited by a stop 33 carried by the plate 23, as illustrated in Figure 6. It will be seen 110 from the latter figure that the movement of the plate 29 totally disengages the two gripping surfaces and consequently the withdrawal of the extremities of the yarns therefrom will not leave any of the strands thereof caught between said surfaces. As soon 115

as the extremities are withdrawn the plate 29 restores, by gravity, to its normal position. After the extremities have again been passed between the delivery rolls, engaged with the hook 22 and connected to the spindle 11, the arm 19 is restored to its normal position and the operation of the machine continues.

There are times when it is necessary to stop the operation of the machine with the result that the tension or downward pull upon each stop motion device is released and the device again assumes its operated position. It is desirable at these times that the device be prevented from coming in contact with the yarns which would result in a severance thereof, and for this purpose means are provided for shifting the yarns to a position where the same will not be contacted by the gripping means when the stop motion device moves to its operated position, this adjustment of the yarns being effected prior to the stopping of the machine. To this end, the rod 16 is carried by an oscillatory arm 34 secured to the end of a shaft 35 rotatably supported in suitable bearings 36 on the frame of the machine. This shaft also carries a disk 37 having notches 38 and 39 therein. When the arm 34 is in its normal or elevated position, as shown in Figure 1, the notch 38 is engaged by a pawl 40 pivoted to the frame of the machine. However, when it is desired to lower the yarns so that they will not be engaged by the gripping means of the stop motion device when the latter is at the extremity of its downward movement, the pawl 40 is first withdrawn from the notch 38 and then by any suitable means, such as a handle (not shown) on the shaft 35, said shaft and consequently the disk 37, together with the arm 34, are swung downwardly until the pawl 40 is engaged with the notch 39. This downward movement will carry the rod 16 to the dotted line position shown in Figure 1, so that the portions of the arm between said rod and the delivery rolls will be disposed in a substantially horizontal plane and out of reach of the gripping means of the stop motion device. The machine may now be stopped and the stop motion devices all permitted to assume their operated positions without affecting the yarns.

What is claimed is:

1. In yarn twisting mechanism, the combination with a frame, delivery rolls supported therein, feeding means from which yarns are drawn to said rolls, and a bobbin for receiving said yarns from said rolls; of a stop motion device including an arm carried by said frame and having a rocking movement relative thereto, means on said arm operable by movement thereof in one direction to engage and grip the yarns at a point between said feeding means and de-

livery rolls to cause said yarns to be severed at said point by the action of said rolls, and means to alter the direction of feed of the yarns to the delivery rolls to prevent engagement thereof by said gripping means when said arm moves to its operative position.

2. In yarn twisting mechanism, the combination with a frame, delivery rolls supported therein, feeding means from which yarns are drawn to said rolls, and a bobbin for receiving said yarns from said rolls; of a stop motion device including an arm pivoted on said frame and engaged at one end thereof by the yarns so that the tension thereof will maintain the device inoperative, gripping means at the other end of said arm operable, upon said tension being relieved, to grip said yarns between said feeding means and delivery rolls to cause the yarns to be severed by the action of said rolls, and means to alter the direction of feed of the yarns to the delivery rolls to prevent engagement thereof by said gripping means when said arm moves to its operative position.

3. A stop motion device for use with yarn twisting mechanism including a pivoted arm held against movement by the yarns being twisted, gripping means carried by said arm and operable upon release thereof by the yarns and consequent movement of the arm about its pivot to engage said yarns to prevent further feeding thereof to the twisting mechanism, said gripping means including a stationary plate having a gripping surface, and a movable plate pivotally supported by said stationary plate and also having a gripping surface cooperating with the surface of the stationary plate and normally engaged therewith to receive the yarns therebetween to cause said yarns to be severed, said movable plate being movable about its pivot in one direction to disengage said surfaces to thereby release the severed yarns.

4. A stop motion device for use with yarn twisting mechanism including a pivoted arm held against movement by the yarns being twisted, gripping means carried by said arm and operable upon release thereof by the yarns and consequent movement of the arm about its pivot to engage said yarns to prevent further feeding thereof to the twisting mechanism, said gripping means including a stationary plate supported upon said arm in diagonal relation thereto and having a beveled gripping surface, and a movable plate pivotally supported by said stationary plate and in substantially the same plane therewith, said movable plate also having a gripping surface normally engaged with the beveled surface of the stationary plate, and said gripping surfaces being adapted to receive the yarns therebetween to cause the same to be severed.

5. A stop motion device for use with yarn twisting mechanism including a pivoted arm

held against movement by the yarns being twisted, gripping means carried by said arm and operable upon release thereof by the yarns and consequent movement of the arm about its pivot to engage said yarns to prevent further feeding thereof to the twisting mechanism, said gripping means including a stationary plate having a gripping surface, an angular arm adjustably supported by said plate, means for securing said arm in adjusted position, a movable plate pivotally supported by said arm and having a gripping surface cooperating with the surface of the stationary plate and normally engaged therewith to receive the yarns therebetween to cause said yarns to be severed, and said movable plate being movable about its pivot to disengage said surfaces to thereby release the severed yarns.

6. In yarn twisting mechanism, the combination of feeding means for the yarn and delivery rolls to which the yarn is fed, adjustable means to guide the yarn in one direction from said feeding means to said rolls, a stop motion device movable to a position to engage the yarn for severing the same, and means for adjusting said guiding means to alter the direction of feed of the yarn to said rolls to prevent engagement of the yarns by said device when the latter moves to its severing position.

7. In yarn twisting mechanism, the combination with a frame, delivery rolls supported therein, a bearing member carried by the frame above said rolls, feeding means from which yarn is drawn to said rolls, and a bobbin for receiving said yarn from said rolls; of a stop motion device including an arm pivoted for rocking movement in said

bearing above said rolls, means for guiding 40 said yarn from said feeding means to said rolls with the yarn extending entirely beneath said arm, and means on said arm operable by movement thereof in one direction about its pivot to engage and grip the yarn 45 at a point between said feeding means and delivery rolls to cause said yarn to be severed at said point by the action of said rolls.

8. A stop motion device for use with yarn twisting mechanism including a pivoted 50 arm, gripping means carried by said arm and operable upon movement thereof in one direction to engage the yarn to prevent further feeding thereof to the twisting mechanism, said gripping means including a stationary gripping surface, and a second surface pivotally movable relative to the first named surface to contact and move away therefrom whereby to grip the yarn therebetween and permit release thereof. 60

9. A stop motion device for use with yarn twisting mechanism including a pivoted arm held against movement by the yarn being twisted, gripping means carried by said arm and operable upon release thereof by the 65 yarn and consequent movement of the arm about its pivot to engage said yarn to prevent further feeding thereof to the twisting mechanism, said gripping means including plates having opposed gripping edges between which the yarn is held when said gripping means is operated, and a mounting for one of said plates permitting movement thereof relative to the other plate to separate said gripping edges. 70

In testimony whereof I have affixed my signature.

JULIUS WYSS.
